Primary Examiner — John Windmuller*Assistant Examiner* — Luqman McNeil(74) *Attorney, Agent, or Firm* — Birch, Stewart, Kolasch & Birch, LLP(57) **CLAIM**

The ornamental design for a mobile phone, as shown and described.

DESCRIPTION

FIG. 1 is a rear perspective view of a mobile phone showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective, view thereof;

FIG. 9 is a rear perspective view thereof showing the state that the camera part at the upper-back side of the mobile phone has been detached; and,

FIG. 10 is a reference view thereof showing the state that the user can wear the detached camera on the wrist.

The broken lines show unclaimed subject matter only and form no part of the claimed design.
